MEAT GRINDER

John H. Osborne, Anderson, Ind.

Application December 31, 1934, Serial No. 759,811

6 Claims. (Cl. 146—189)

The object of my invention is to provide certain improvements in details of construction of a meat grinder wherein desired relation between the perforated cutter plate and the relatively movable knife may be determined and established independent of the main shell of the grinder.

The accompanying drawing illustrates my invention.

Fig. 1 is a vertical axial section of a meat grinder of the screw impeller type embodying one form of my invention;

Fig. 2 is a fragmentary vertical section; and

Fig. 3 is a fragmentary axial section of another form of a reversible cutter plate which may be readily associated with existing grinders.

In the drawing 10 indicates the casing, of usual form, of a common form of meat grinder and comprising hopper 11 and pressure chamber 12, the open mouth of which is provided with external threads 13 adapted to receive ring nut 14 capable of retaining, between it and the open end of the pressure chamber 12, the perforated cutter plate 15 which is held against rotation by pin 16 carried by casing 10 and projecting into a peripheral notch 17 in plate 15. Thus far the structure is common and well-known. Rotatably mounted within casing 10 is a pressure screw 18 which subtends the discharge end of hopper 11 and projects into the vicinity of plate 15. Between the discharge end of screw 18 and the inner face of plate 15 is a cutter 19 comprising a series of radial cutter arms which contact the inner face of plate 15.

Heretofore it has been customary to establish desired contact between the inner face of the cutter plate 15 and the cutter arms of cutter 19 by forcing plate 15 into contact with the cutter by the nut 14, the thrust developed by this contacting being resisted by a thrust washer 20 interposed between the receiving end of screw 18 and an adjacent portion of casing 10.

In such an arrangement nut 14 must be set very tightly to position and the pressure developed by the screw through the meat upon the plate 15 tends to separate cutter 19 from the inner face of plate 15, and the development of this pressure often makes it necessary to further tighten nut 14. As a consequence, these ring nuts 14 are often broken and the total frictional resistance developed by the thrust bearing 20 and the contacting of the cutter with the plate requires the exertion of a very considerable amount of torque to produce rotation of the pressure screw and cutter.

Referring now to Fig. 1. The delivery end of

screw 18 is provided with an axial bore 25 threaded at 26 to receive a sleeve 27 shouldered at 28 to permit firm seating in screw 18 and provided at its outer end with a polygonal portion 29 adapted to fit in and cause rotation of cutter 19. Mounted in the bore of sleeve 27 is a spindle 30 having, at an intermediate point, a polygonal collar 31 lying within a correspondingly shaped central opening in plate 15. Mounted upon spindle 30 at the inner end of sleeve 27 is a thrust washer 32 which is held axially in position in contact with the inner end of sleeve 27 by a nut 33 threaded upon the inner end of spindle 30 as indicated at 34. The outer end 30' of spindle 30 is threaded at 35 to receive a nut 36 adapted at one end to contact plate 15 and provided at its free end with a knurled head 37 by means of which it may be readily manipulated.

With this construction ring nut 14 does not need to be tightly positioned. Tightening of nut 36 against the outer face of plate 15 will serve to draw cutter 19 into contact with the inner face of plate 15 and the thrust developed by the pressure of meat against the inner face of plate 15 through the meat, due to the action of the screw 18, will be taken by the thrust washer 32. As this thrust washer lies within the bore 25, where it is thoroughly protected from the meat by the tight joint established by collar 28, adequate lubricant may be maintained, within bore 25, for the thrust washer 32, without possibility of contaminating the meat, and plate 15 floats between the outer end of casing 10 and the ring nut 14. Rotation of spindle 30 is prevented by reason of the non-rotative connection, at 31, between said spindle and plate 15, and the non-rotative association of plate 15 with casing 10 at 16—17. The entire end thrust developed by screw 18 will thus be taken by the discharge end of casing 10, through plate 15, so that washer 20 may either be eliminated or used merely for the purpose of protecting the spindle of screw 18 from the material delivered into hopper 11.

Referring now to the construction shown in Fig. 2.—Screw 18 is provided with a bore 25' within which sleeve 27' is splined, as indicated at S. Sleeve 27', shouldered at 27'', is provided with a polygonal outer end 29 upon which the cutter 19 is mounted, as in the other form. Projected through the bore of sleeve 27' is spindle 30' provided with the polygonal intermediate portion 31, and an outer threaded portion 30' to receive the nut 36. On the inner end of this spindle, as in the other form, there is the thrust washer 32 retained by nut 33.

In this form the thrust, toward the left, produced upon the screw 18 by the meat, must be taken by a thrust bearing as indicated at 20 in Fig. 1, and this thrust, owing to the splined connection S, has no effect upon the adjustment of cutter 19 relative to plate 15.

Referring to Fig. 3, pressure screw 18 is counterbored, at 25, as shown in Fig. 1. This counterbore is provided with threads 26 into which sleeve 27 is threaded and firmly seated. Sleeve 27 is provided at its outer end with a polygonal portion 29 to receive the cutter 19. A perforated cutter plate 15' is axially perforated at 15", to receive, in either axial direction, one end of a spindle 300 which is provided with an integral plate-engaging collar 301. The spindle 300 is held in place in the plate 15' by nut 302 and the unthreaded end of this spindle is projected into the bore of sleeve 27.

20 It will be noted that in this form the spindle 300 may be reversed in plate 15', so that either face of the plate may be readily presented to the cutter.

It will also be noted that, in all of the forms shown, the bearing for the delivery end of the screw 18 is within said screw, instead of being within the perforated cutter plate, as has heretofore been the custom. As a consequence of this construction it is possible to provide a much 25 longer bearing for the delivery end of the pressure screw than has heretofore been possible and this bearing is protected from the meat so that, even though the bearing be considerably worn, there is no tendency for meat to crowd into the bearing where it is likely to be overlooked and become putrid.

In the form shown in Fig. 3, the pressure screw 18 must be provided with a thrust bearing like the thrust bearing 20 in Fig. 1, and the cutting 40 relation between the cutter 19 and the plate 15' must be determined by the ring nut 14.

I claim as my invention:

1. In a meat grinder, the combination with the cutter plate and pressure screw, of a cutter interposed between said plate and screw and rotatable by the screw, a spindle nonrotatively associated with the plate and projected into the pressure screw, means carried by said spindle, within the pressure screw, for preventing relative 45 axial movement in one direction of the screw relative to the plate, but permitting relative rotative movement between the spindle and cutter, and means carried by the outer end of the spindle, for engaging the cutter plate adjustably in op- 50 position to the cutter.

2. In a meat grinder, the combination with

the cutter plate and pressure screw, of a thimble mounted in an axial bore of said screw for rotation with the screw, a cutter interposed between the screw and plate and rotatable with the screw, a spindle nonrotatably associated with the plate 5 and projected through the thimble into the bore of the screw, means carried at the inner end of said spindle for axially engaging the thimble to hold the cutter against the plate, and means carried by the outer end of the spindle for engaging 10 the cutter plate adjustably in opposition to the cutter.

3. In a meat grinder, the combination with the cutter plate and pressure screw, of a cutter interposed between said plate and screw and rotatable with the screw, a thimble splined within the screw and having an axial abutment for the cutter, a spindle nonrotatively associated with the plate and projected through said thimble, means carried by the spindle within the pressure screw 20 for preventing axial movement of the spindle relative to the thimble in one direction and to hold the cutter against the plate, but permitting rotation of the thimble upon the spindle, and means carried by the outer end of the spindle for engaging 25 the cutter plate adjustably in opposition to the cutter.

4. In a meat cutter, the combination with the main shell, pressure screw, perforated cutter plate, and cutter non-rotatively associated with the 30 pressure screw, of a bearing formed axially within the delivery end of the pressure screw, and a spindle non-rotatively associated with the perforated cutter plate and projected inwardly into said bearing, the pressure screw being rotative 35 thereon.

5. A meat cutter structure of the character specified in the immediately preceding claim wherein the spindle is provided, intermediate its length, with a plate engaging shoulder and the 40 spindle is reversibly associated with the plate by a removable nut threaded upon the outer end of the spindle and engaging the outer face of the plate.

6. In a meat cutter, the combination with the 45 main body and cutter plate non-rotatively engaging one end thereof, of a pressure screw rotatable within the main body, a cutter non-rotatively associated with the pressure screw between the pressure screw and the cutter plate, a thrust bearing interposed between the pressure screw and cutter plate to transfer the screw-thrust to the plate, and means by which the axial 50 relation of cutter and cutter plate may be adjusted.

JOHN H. OSBORNE.
